UNITED STATES PATENT OFFICE.

WILLIAM J. RUEDISALE, OF DETROIT, MICHIGAN.

DESIGN FOR A FISH-SCALER.

SPECIFICATION forming part of Design No. 23,752, dated October 30, 1894.

Application filed September 25, 1894. Serial No. 524,118. Term of patent 7 years.

To all whom it may concern:

Be it known that I, WILLIAM J. RUEDISALE, a citizen of the United States, residing at Detroit, in the county of Wayne and State 5 of Michigan, have invented and produced a new and original Design for a Fish-Scaler, of which the following is a specification, reference being had therein to the accompanying drawings, in which—

Figure 1 is a bottom plan view. Fig. 2 is a side elevation, and Fig. 3 is a top plan view.

The leading feature of the design is the configuration thereof, comprising a curved, toothed body and a curved handle enlarging 15 toward its end.

A is the body, substantially rectangular, with rounded corners, and having the gracefully curved top B, the curved under face D,

from which project the rectangular teeth D', the under faces of which form a curve parallel with the lines of the body. The handle has a graceful curve in its length and gradually enlarging toward its end, which is rounded off. The lines on the sides and top of the handle merge by graceful lines into 25 the lines of the body A.

What I claim as my invention is—
The design for a fish scaler herein described and shown.

In testimony whereof I affix my signature in 30 presence of two witnesses.

WILLIAM J. RUEDISALE.

Witnesses:

M. B. O'DOGHERTY,
L. J. WHITTEMORE.
